INVENTOR.

John Nation,

BY

Geo. F. Kimmel

ATTORNEY.

UNITED STATES PATENT OFFICE

JOHN NATION, OF HIGHMORE, SOUTH DAKOTA

WRENCH

Application filed October 26, 1928. Serial No. 315,243.

This invention relates to a wrench and has for its primary object to provide, in a manner as hereinafter set forth, a tool of the above class having a pair of jaws formed in a manner whereby they are adapted to grip cylindrical or hexagonal objects of different sizes without the necessity of any adjustment of the parts of the tool.

A further object of the invention is to provide a tool having a pair of jaws as aforesaid which are formed with opposing angular faces and wherein one jaw projects materially beyond the forward end of the other.

With the foregoing and other objects in view the invention consists in the novel construction, combination and arrangement of parts as hereinafter more particularly described and illustrated in the accompanying drawings, wherein for the purpose of illustration is shown an embodiment of my invention, but it is to be understood that changes, variations and modifications may be resorted to which fall within the scope of the invention as claimed.

In the accompanying drawings in which like numerals are employed to designate like parts throughout the same,

Figure 1 is a perspective view of a wrench constructed in accordance with this invention.

Figure 2 is a fragmentary side elevation thereof showing its jaws in gripping position on a piece of pipe.

Figure 3 is a fragmentary top plan of the embodiment illustrated in Figure 1.

Referring to the drawings in detail the numerals 1 and 2 respectively designate a pair of handle members formed with angularly disposed, flat portions 3 crossing each other and pivoted together by means of a suitable pin 4. Formed integrally with the flattened portions 3 of the handles 1 and 2 respectively is a lower jaw 5 and an upper jaw 6, with the forward end of the lower jaw 5 projecting materially beyond the forward end of the upper jaw. The upper jaw 6 is formed with an inwardly offset portion 7 and the lower jaw 5 is formed with an inwardly offset portion 8, said offset portions 7 and 8 providing the extreme forward ends of the

jaws with equal widths and with such extreme forward ends being in alignment with respect to the length of the wrench.

The lower jaw 5 is formed at its extreme forward end with an upturned nose 9 whereby the gripping face of the jaw 5 is formed with an angle 10. The rear face of the upturned nose 9 is formed with a plurality of transversely extending teeth 11.

The lower face of the upper jaw 6, at the forward end thereof, is formed with an inverted V-shaped notch to provide an angle 11, the forward wall 12 of which is of less length than its rearward wall 13. The angle 11 is of lesser degree than the angle 10 and the vertical plane thereof is disposed rearwardly of the vertical plane of the angle 10.

When the jaws 5 and 6 are engaged with a pipe, as indicated at 14 in Figure 2, the walls 12 and 13 of the angle 11 engage the wall of the pipe to force the same into the angle 10 formed in the lower jaw 5. The upper face of the enlarged portion 8 of the jaw 5 and the rearward wall 13 of the angle 11 are disposed at converging angles and resist the displacement of the pipe in a rearward direction to enable the teeth 11 to bite into the wall of the pipe. Movement of the jaws 5 and 6 about the pivot pin 4 to open or close the jaws changes the relative disposition of the angles 10 and 11 whereby pipes of different sizes may be forced into the angle 10 to be engaged by the teeth 11.

It is to be understood that the embodiment of the invention herewith shown and described is to be taken as the preferred example of the same and that various changes in the details of construction may be resorted to without departing from the spirit of the invention or the scope of the appended claims.

What I claim is:

A wrench comprising, a pair of substantially parallel handle members having oppositely inclined anchor portions intersecting each other and pivotally connected together, one of said anchor portions merging at its forward end into a jaw member extending in a plane substantially parallel to the longitudinal plane of the handle member with which the anchor portion merging into

the jaw member is formed, said jaw member being formed at its forward end with an upturned portion whereby the jaw member is provided with an angular gripping face disposed forwardly of and in spaced relation to the anchor portion merging thereinto, teeth provided on the upturned portion of said gripping face, the other of said anchor portions merging at its forward end into a jaw member extending in a plane substantially parallel to the longitudinal plane of the other handle member and having a flat face formed adjacent its forward end with an angular recess to provide an angular gripping face at the forward end of said last named jaw member and merging into the flat face thereof in spaced relation to the inclined anchor portion merging thereinto.

In testimony whereof, I affix my signature
20 hereto.

JOHN NATION.
